L. HAIN.
DETACHABLE HEEL SECTION.
APPLICATION FILED MAY 6, 1914.

Patented Apr. 6, 1915.

UNITED STATES PATENT OFFICE.

LEON HAIN, OF PHILADELPHIA, PENNSYLVANIA, ASSIGNOR OF ONE-HALF TO JOHN NELSON, OF PHILADELPHIA, PENNSYLVANIA.

DETACHABLE HEEL-SECTION.

1,134,263.

Specification of Letters Patent.

Patented Apr. 6, 1915.

Application filed May 6, 1914. Serial No. 836,635.

To all whom it may concern:

Be it known that I, LEON HAIN, a subject of the Czar of Russia, residing at Philadelphia, in the county of Philadelphia and 5 State of Pennsylvania, have invented certain new and useful Improvements in Detachable Heel-Sections, of which the following is a specification.

My invention relates to improvements in 10 detachable heel sections, the object of the invention being to provide a boot or shoe with a permanent heel section and a removable heel section comprising the lower portion of the heel, so that when the removable 15 heel section is worn, it may be replaced by a new heel section without the necessity of having the heel repaired by a skilled shoe maker.

A further object is to provide improvements of this character which when in position, will resemble the ordinary heel, and will have a firm locking juncture, so that the section cannot work loose or be released.

A further object is to provide improvements of the character stated which are of extremely simple construction, neat and attractive in appearance, strong and durable in use.

With these and other objects in view, the 30 invention consists in certain novel features of construction and combinations and arrangements of parts as will be more fully hereinafter described and pointed out in the claims.

35 In the accompanying drawings: Figure 1 is a fragmentary view in longitudinal section illustrating my improvements. Fig. 2 is a view in transverse section on the line 2—2 of Fig. 1. Fig. 3 is a bottom plan view 40 of the permanent heel section. Fig. 4 is a top plan view of the removable heel section. Fig. 5 is a view in transverse section illustrating a modified form of removable heel section.

45 1 represents a boot or shoe, and 2 a permanent heel section which is formed on the shoe in the ordinary manner, and which is provided on its lower face with a metal plate 3. This plate 3 conforms in shape to 50 the shape of the heel. It is appreciably smaller than the heel and extends to the front edge of the heel where it is provided with a recess 4. The outer edge of the plate 3 is concentric with the outer edge of the 55 heel, and is beveled as shown at 5. The

plate 3 may be secured to the heel in various ways. I have indicated small screws 6 for the purpose, but do not limit myself to this particular means.

7 represents my improved removable heel section. This section 7 may be of leather, rubber, or any other suitable material, and conforms in shape to the shape of the rigid heel section, so that when the sections are together, they give the appearance of an ordinary heel. On the upper face of the removable section 7, I secure a thin steel plate 8 having a U-shaped metal frame 9 secured thereto by rivets 10. In other words, the plate 8 and frame 9 are rigidly secured together by the rivets 10, and screws or other suitable securing devices 11 are projected through openings in the frame 9 and plate 8 and screwed into the removable section 7. In the preferred form of my invention, the upper face of the removable section is recessed to accommodate the plate 8 and frame 9, so that the leather or other material of the section extends to the upper edge of the removable section, and entirely hides the metal.

55 In the modification illustrated in Fig. 5, the plate 8 and frame 9 extend entirely to the edge of the removable section in which case I shall preferably so color the metal that it will not attract attention. The plate 8 is formed of thin steel ribbon, and at its forward edge is provided with two recesses 12 which form between them, a spring tongue 13 having a block 14 fixed to the free end of the tongue and constituting a spring catch, said block engaging in the recess 4 of the plate 3. The inner face of said blocks is undercut or inclined downwardly and inwardly as at 14', while the adjacent forward face of said permanent heel section is correspondingly inclined as at 15', to receive the beveled face 14' of the said block 14 in locking engagement when the removable heel section is properly adjusted to the shoe heel proper, and by this arrangement it is obvious that the removable heel section will not only be locked against sliding movement but the forward edge, as well as the other edges thereof, will be held against sagging or dropping downwardly. The removable section 7, at its forward edge, has a recess 15 back of the spring tongue or catch so as to allow the latter a sufficient movement to release itself from engagement with the recess 110

4 of plate 3. The inner edge of frame 9 is beveled or inclined as shown at 16, so that it forms a dove-tail juncture with the plate 3 when the removable section is moved longitudinally.

Fig. 1 shows the parts in normal position. When the removable section is worn, it is simply necessary to insert the finger nail or some instrument between the block 14 and the permanent heel section 2, and press the block downwardly out of the recess 4. This engagement of the block is facilitated by reason of the fact that the forward edge of the block is beveled as shown at 17, and it will also be noted that the forward ends of the frame 9 are beveled as shown at 18 to prevent cutting the leather of the permanent heel section when the removable section is moved longitudinally. Furthermore, these beveled portions 17 and 18 facilitate the assemblage of the removable heel section, as they serve to guide the parts together when pressure is applied as well as longitudinal movement. After the block 14 is pressed out of the recess 4, the section 7 can be slid rearwardly and removed. A new section can then be inserted, and the heel will be like new. It will be observed that when the parts are together, that the plate 8 forms a smooth contacting surface engaging the plate 3 throughout the entire surface of the latter, and as the plate 3 and frame 9 are of the same thickness, the heel sections will lie smoothly together and there will be no uneven contacting surfaces to interfere with the perfect connection.

It is to be understood that it is my purpose to supply to the trade, removable heel sections of various sizes and shapes, so that any purchaser can obtain the heels and repair his own shoes in this manner without the necessity of employing skilled labor. In other words, every purchaser of a pair of shoes will know the size of heel section he will want, and when the section becomes worn, he can obtain a new one and place it on a shoe.

Various slight changes might be made in the general form and arrangement of parts described without departing from my invention, and hence I do not limit myself to the

precise details set forth, but consider myself at liberty to make such changes and alterations as fairly fall within the spirit and scope of the appended claims.

55

Having thus described my invention, what I claim as new and desire to secure by Letters Patent is:

1. A permanent heel section having a plate secured to its lower face with its forward edge flush with the forward edge of said heel, the said forward edge of said plate being recessed and the rear edge of said recess being beveled, in combination with a removable heel section, said removable heel section being provided with a plate having its forward edge flush with the forward edge of the section to which it is attached and provided with means to interlock with the edges of the plate on said permanent heel section, said forward edge of said plate being cut away to provide a spring tongue, and a block secured to said tongue to extend upwardly therefrom and provided at its inner edge with a beveled surface for locking engagement with the beveled edge of the recess on said permanent heel section, substantially as described.

60

2. The combination with a permanent heel section and a removable heel section arranged in sliding interlocking engagement with each other, of a spring tongue formed upon said latter heel section flush with the forward edge thereof and provided with an upwardly and inwardly extending block, the said permanent heel section having its forward edge adjacent said block inclined inwardly and upwardly, and the inner face of said block being inclined downwardly and inwardly for engagement with the said forward face of said permanent heel section, whereby said removable section will be held against sliding movement and the forward edge thereof will be held against downward movement, substantially as described.

9

In testimony whereof I have signed my name to this specification in the presence of two subscribing witnesses.

LEON HAIN.
